UNITED STATES PATENT OFFICE.

WILLIAM M. DALY, OF PHILADELPHIA, PENNSYLVANIA.

LEDGER-INDEX.

SPECIFICATION forming part of Letters Patent No. 603,944, dated May 10, 1898.

Application filed September 30, 1897. Serial No. 653,641. (No model.)

To all whom it may concern:

Be it known that I, WILLIAM M. DALY, a citizen of the United States, residing at Philadelphia, in the county of Philadelphia and State 5 of Pennsylvania, have invented certain new and useful Improvements in Ledger-Indexes; and I do hereby declare the following to be a full, clear, and exact description of the invention, such as will enable others skilled in the 10 art to which it appertains to make and use the same.

My invention has relation to index attachments for account-books, such as bank-ledgers, whereby the state of the account or 15 balance remaining or due can be ascertained at a glance; and it consists in the combination, with an account-book, of one or more readily-detachable slates or sheets of paste-board covered with a silicious coating.

20 My invention further consists in the construction, combination, and arrangement of parts more fully described hereinafter and specifically pointed out in the claim.

In the accompanying drawings, forming part 25 of this specification, Figure 1 shows an opened ledger having my improved index in position thereon; and Fig. 2, an end view of a closed book, while Fig. 3 shows the index and its frame detached from the book.

30 In the drawings, A represents the ledger, the covers B and C of which project beyond the leaves D of the ledger. Interleaved with these are stiff sheets E, which project beyond the edge of the ledger-leaves nearly or quite 35 to the edges of the covers. Attached to each of these sheets E is a light metallic or sheet-

metal casing F, having its two side edges *ff* and its upper edge *g* upset, so as to form a receptacle, in which the slate H may be readily inserted. This metallic frame F may be attached either by cementing it to the sheet or it may be attached with light rivets, so as to become a permanent fixture not readily detached or displaced.

It will be seen that the slate H may be used 45 to carry the balances of several accounts and that when it is desirable or necessary to make an erasure or any other change on the slate it is readily slipped from its position in the holder, and after the correction is made it is 50 replaced in its original position, and if through use or accident the slate becomes worn or injured a new one can be utilized without in any way injuring the book. It is evident that the slate can be used on either side by simply 55 withdrawing it and inserting with the reverse side up.

Having described my invention, I claim—

The combination with an account-book having sheets projecting beyond the edges of the 60 leaves of the book, of the retaining-frames secured to said extended sheets, and the slates adapted to slide within and be retained in position by said frames, substantially as described.

In testimony whereof I affix my signature in presence of two witnesses.

WILLIAM M. DALY.
